(76) Inventor: **Hsing-Wen Yeh**, Taichung (TW)

* cited by examiner

(**) Term: **14 Years**

Primary Examiner — Derrick Holland

(21) Appl. No.: **29/402,577**

(74) *Attorney, Agent, or Firm* — Muncy, Geissler, Olds & Lowe, PLLC

(22) Filed: **Sep. 23, 2011**

(57) **CLAIM**

(51) **LOC (9) Cl.** **13-02**

I claim the ornamental design for a solar powered ventilation assembly, as shown and described.

(52) **U.S. Cl.** **D13/102**

DESCRIPTION

(58) **Field of Classification Search** D13/102,
D13/101, 107, 184, 199; D25/55, 57; 52/74,
52/77, 78, 173.3; 126/569, 571, 577, 600,
126/603, 605, 606, 608; 136/243—246, 251;
320/101

See application file for complete search history.

FIG. 1 is a right, front perspective view of the solar powered ventilation assembly showing my new design;

FIG. 2 is a front view with the top open thereof;

FIG. 3 is a rear view with the top open thereof;

FIG. 4 is a left view thereof;

FIG. 5 is a right view thereof;

FIG. 6 is a top plan view thereof;

FIG. 7 is a bottom plan view thereof; and,

FIG. 8 is a right, rear perspective view of the solar powered ventilation assembly.
